UNITED STATES PATENT OFFICE.

GLEN KNOX, OF GUNN, WYOMING, ASSIGNOR TO LINK-BELT COMPANY, OF CHICAGO, ILLINOIS, A CORPORATION OF ILLINOIS.

LOADING BOOM.

Application filed March 22, 1923. Serial No. 626,744.

My invention relates to a loading boom for delivering relatively finely divided materials, such as coal, to railroad cars or other conveyors. It has for particular purpose to 5 provide a boom adapted to deliver coal to a mixed train wherein some of the cars are box cars and some are open topped. A further object is to provide a boom of the class described which receives coal from a 10 source lower than the top of a box car. Other objects will appear from time to time in the course of the specification and claim.

I illustrate my invention more or less diagrammatically in the accompanying drawings wherein—

Figure 1 is a side elevation with parts in section;

Figure 2 is a plan view.

Like parts are illustrated by like symbols 20 throughout the specification and drawings.

A, A are the structural members of any suitable tipple, the details of which form no part of the present application. A¹ is the end of any suitable type of shaking or 25 delivery chute or screen down which coal or some similar material may be discharged.

B is a loading boom which is pivoted as at B¹ in the yoke B² upon a horizontal axis. The yoke B² is in turn pivoted on a swivel 30 and adapted to rotate about a bolt B³ which is mounted in the block B⁴ for the purpose of which any bearing surface or member B⁵ is provided.

C is a track herein shown as an I-beam 35 which is supported in any suitable manner, for example upon the A-frames C¹, C⁴, and over-lies the outer end of the boom B. Adapted to travel along the track is any suitable supporting element C² provided 40 with upwardly and inwardly extending arms C³, terminating in rollers C⁴, adapted to ride along the lower flanges of the track C. Any suitable means are provided for manually or mechanically drawing the element C² back 45 and forth along the track C to rotate the boom B about its pivot. The height of the outer end of the boom is controlled, for example, through the pulleys D, D, the cable D² and hoist C².

D¹⁰ is a cable passing around the sheaves D¹¹, D¹² and secured at each end to the supporting element C². D¹⁴ is a pulley adapted to rotate the sheave D¹² and thus actuate the cable D¹⁰ to rotate the boom B about the 50 vertical pivot. D¹⁵ is a driving belt extend-

ing to any suitable power source not herein shown.

D⁴ is any suitable depending yoke, its arms being pivoted at the lower ends as at D⁵ to the boom B.

The outer end of the boom, preferably adjacent its connection to said yoke, is downwardly inclined as at B¹⁰.

The boom may be constructed in any suitable manner and is herein shown as provided at its upper end with any suitable motor E which, through the chain of gears E¹, drives the belt or conveyor sprocket E² about which passes the endless conveyor E⁴ which extends throughout substantially the entire length of the boom and passes about the terminal sprocket E⁵, the belt being guided and supported in any suitable manner along the length of the boom. E⁶ is any suitable picking table platform mounted at one side of the boom.

It will be realized that while I have illustrated a working mechanism, many changes might be made in the size, shape, number and disposition of parts without departing from the spirit of my invention.

The use and operation of my invention are as follows:

In many coaling plants, the point of delivery of the chute or screen is lower than the necessary clearance for a box car. It therefore becomes desirable that when box cars, as well as open cars, are to be filled by a loading boom that the boom be pivoted at a point lower than the top of the box car. This necessarily involves pivoting the boom to one side of the track along which the cars are to be propelled. It also necessitates a boom which, while pivoted at a lower point, is so shaped that it can deposit coal at the bottom of a box car without dropping it so as to cause breakage.

The loading boom I employ is of the endless conveyor type, having a belt or conveyor which positively conveys the coal deposited on one end of the boom to the other end of the boom, regardless of the angle at which the boom is positioned. To enable this boom when pivoted at one end at a point below the top of a box car, to deliver coal not merely to the open door of the box car, but over the edge and to the bottom of an open car, I provide it with a downwardly inclined end section. This permits it to deliver coal directly to the

- bottom of an open car though the upper or inner section of the boom is in a practically horizontal position. This is illustrated in full lines in Figure 1. The boom, 5 being pivoted to one side of the track, necessarily delivers its coal along a path inclined to the longitudinal axis of a car, as shown in Figure 2. The boom being pivoted on a horizontal as well as a vertical pivot, it 10 may be raised and lowered to compensate for various heights of cars and to permit the end to be dropped into the car bottom and to be lifted from the car when the car is filled. The car, of course, may be moved 15 progressively forward as the coal is deposited, until it is filled from end to end, and the boom is then lifted to permit the car to pass on.
- When a box car is to be filled the boom 20 is not merely lifted, but is swung about its vertical pivot until it lies parallel with and along the side of the track, as shown in dotted lines in Figure 2. The box car is preferably spotted with its central door opposite the end of the boom and any suitable coaling chute is provided to receive the coal from the boom and deliver it through the box car door, the end of such a chute being diagrammatically illustrated by 25 dotted lines in Figures 1 and 2. Preferably a box car loading device of any suit-

able type is used, the details of which form no part of the present invention, but the coal delivered to the box car may, of course, be distributed in the box car by manual labor 35 if so desired.

I provide my boom with a picking table along which several operatives may stand and pick slate or other refuse from the coal as it passes down the boom. 40

I claim:

In association with a car supporting track, a material delivery means located at one side of the track, a loading boom pivoted adjacent said material delivery means, and adapted to receive material therefrom, said boom being rotatable about both a horizontal and a vertical pivot, means for raising and lowering said boom about said horizontal pivot, and for rotating it about said vertical pivot to swing the outer end of the boom over the track, the length of the boom being substantially greater than the distance between the vertical pivot and the track, the outer end of the boom being downwardly inclined in relation to and integral with the body of the boom. 50 55

Signed at Gunn, county of Sweetwater and State of Wyoming, this 13 day of March, 1923.

GLEN KNOX.
